Primary Examiner — Omeed Agilee(57) **CLAIM**

The ornamental design for a cartridge with sample holder, as shown and described.

DESCRIPTION

FIG. 1 is a perspective view of a cartridge with sample holder in a closed configuration showing our new design; FIG. 2 is a front view of the design of FIG. 1; FIG. 3 is a back view of the design of FIG. 1; FIG. 4 is a first side view of the design of FIG. 1; FIG. 5 is a second side view of the design of FIG. 1; FIG. 6 is a top view of the design of FIG. 1; FIG. 7 is a bottom view of the design of FIG. 1; FIG. 8 is a perspective view of the cartridge with sample holder in an open configuration; FIG. 9 is a front view of the design of FIG. 8; FIG. 10 is a back view of the design of FIG. 8; FIG. 11 is a first side view of the design of FIG. 8; FIG. 12 is a second side view of the design of FIG. 8; FIG. 13 is a top view of the design of FIG. 8; and, FIG. 14 is a bottom view of the design of FIG. 8. The broken lines depict portions of the cartridge with sample holder that form no part of the claimed design.
